Primary Examiner — Darcey E Gottschalk(74) *Attorney, Agent, or Firm* — Cooper & Dunham LLP(57) **CLAIM**

The ornamental design for a blood occlusion cuff, as shown and described.

DESCRIPTION

FIG. 1 is an isometric view of the blood occlusion cuff showing my new design;

FIG. 2 is an isometric view thereof;

FIG. 3 is a front view thereof;

FIG. 4 is a top view thereof;

FIG. 5 is a bottom view thereof;

FIG. 6 is a right view thereof; and,

FIG. 7 is a left view thereof.

In the drawings, the broken lines show portions of a blood occlusion cuff that form no part of the claim.

The outermost of the two circular broken lines in FIGS. 1-3 represents an inner bound of the claimed design.
